UNITED STATES PATENT OFFICE.

THOMAS JOHNSON, OF ST. LOUIS, MISSOURI, ASSIGNOR TO JOHNSON & BRANDON, OF SAME PLACE.

DESIGN FOR A VAPOR-STOVE.

SPECIFICATION forming part of Design No. 19,198, dated July 9, 1889.

Application filed May 29, 1889. Serial No. 312,665. Term of patent 14 years.

To all whom it may concern:

Be it known that I, THOMAS JOHNSON, a citizen of the United States, residing at St. Louis, in the State of Missouri, have invented and 5 produced a new and original Design for Vapor-Stoves, of which the following is a specification, reference being had to the accompanying drawing, forming part thereof.

The drawing is a perspective view illustrating my design.

The leading feature of my design consists in a rectangular hood located on a vapor-stove.

I represents a vapor-stove. Over the stove are surfaces 2, 3, and 4, arranged in rectangular form, providing a hood, as shown in the drawing. On top of the surfaces 2, 3, and 4 is a surface 5, having an opening 6.

I claim as my invention—

The design for a hooded vapor-stove, substantially as herein described and shown.

THOS. JOHNSON.
